UNITED STATES PATENT OFFICE.

GEORGE WASHINGTON BROMLEY, OF LAKE VIEW, NEW JERSEY.

WINDING-MACHINE.

No. 812,012.

Specification of Letters Patent.

Patented Feb. 6, 1906.

Application filed April 11, 1905. Serial No. 254,987.

To all whom it may concern:

Be it known that I, GEORGE WASHINGTON BROMLEY, a citizen of the United States, residing in Lake View, Passaic county, State of New Jersey, have invented certain new and useful Improvements in Winding-Machines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The object of this invention is to increase the output of a winding-machine of the type illustrated in the United States Patent to Wardwell, No. 589,587, by multiplying in a practical manner the number of winding units.

My invention consists in certain combinations and arrangements of parts hereinafter set forth, whereby this object is attained.

In the accompanying drawings, Figure 1 is a front elevation of my improved winding-machine. Fig. 2 is a side view of the upper portion thereof looking from the right in Fig. 1, and Fig. 3 is a vertical sectional view taken just to the right of the pulleys *c* in Fig. 1.

In said drawings, *a* is the frame. *b* is the main shaft carrying fast and loose pulleys *c*, adapted to be driven from a belt *d*. *e* is a fixed shaft carrying brackets *f*, in which are mounted studs *g*, alined with shaft *b* and adapted, with said shaft *b*, to axially support bobbins or cop-tubes *h*, which may be connected with the shaft *b* in such manner as to be driven thereby. *i* is the slide-rod or traverse-rail carrying thread-guides *j*, adapted to play back and forth parallel with the respective bobbins or cop-tubes, whereby to lay the threads evenly on said bobbins or cop-tubes. *k* is a cam mounted on a cam-shaft *l*, journaled in frame *a* and receiving in its cam-groove *m* a roller *n* on an arm *o*, fixed to the traverse-rail *i*, and *p* is a shaft journaled in a frame *r*, fulcrumed on shaft *l* in frame *a*, said shaft *p* carrying a pulley *t*, over which and a pulley *u* on shaft *b* a belt *v* extends, acting both as a supporting-sling and a means for rotating shaft *p*, and consequently shaft *l*, said shafts *p* and *l* being connected by gearing *w*. All these parts will be found more fully described in the patent above referred to and need no further explanation herein.

In bearings *x* in the frame is journaled a

supplemental shaft *y*, which is driven by a belt *z*, passing over pulley *u* on shaft *b* and a pulley *z'* on shaft *y*. Shaft *y* is kept from lengthwise movement by collars *1*, interposed between and abutting against the two bearings *x*.

On each end of fixed shaft *e* is arranged an upright *2*. Its lower end is penetrated by shaft *e*, and it is adjustably secured thereon by a set-screw *3*. The upper end of the upright *2* is penetrated by a horizontal rod *4*, which is adjustably secured therein by a set-screw *5*. *6* is a bracket supplemental to and substantially like bracket *f* and carrying a supplemental stud *7*, alined with the end of shaft *y* and coacting therewith to support a supplemental bobbin or cop-tube *8* in such manner that the bobbin or cop-tube is rotated from shaft *y*.

On each end of the traverse-rail *i* is secured another upright *9*. This is likewise held adjustably on the traverse-rail by means of a set-screw *10*, and it carries in its upper end a horizontal rod *11*, which penetrates it and is adjustably secured therein by a set-screw *12*. Said rod carries a supplemental thread-guide *13*, which when the traverse-rail reciprocates plays back and forth parallel with the bobbin or cop-tube *8*, so as to lay the threads evenly on the latter.

In a U-shaped rocking bar *14*, formed with lugs *15*, whereby said rocking bar is fulcrumed on the shaft *e*, is pivoted on a screw *16* a loop-shaped belt-shifter *17*, which when moved on said screw *16* as a pivot moves the belt *d* from one pulley *c* to the other. When the belt is on its fast pulley, (the position shown in Fig. 1,) belt-shifter *17* engages a notch *18* in frame *a*, and is thereby prevented from shifting the belt under the tension of a spring *19*, which normally tends to effect this. When the rocking bar *14* is, however, pressed backward, the belt-shifter is disengaged from the notch and spring *19* pulls it over. In order that upon the completion of the winding of a cop this mechanism may automatically act to shift the belt and stop the machine, the upper ends of rocking bar *14* carry horizontal arms *20*, carrying pivoted wipers *21* in proximity to the cops on bobbins *h*, such arms being adjustable in the rocking bar by thumb-nuts *22*. This mechanism is extended so as to supplement it for the upper or supplemental cops by securing between each end of rocking bar *14* and one of the thumb-nuts *22* an extension-arm *23*, in which is adjustably

secured by thumb-nuts 24, a horizontal arm 25, carrying a wiper 26, extending in proximity to the adjacent cop on cop-tube 8.

Having thus fully described my invention, 5 what I claim as new, and desire to secure by Letters Patent, is—

The combination of the frame, two rotary bobbin-driving shafts arranged parallel with each other, a traverse-rail, thread-guides, one 10 for each shaft and one of them being carried by said traverse-rail, means for supporting the other thread-guide on said traverse-rail, a fixed shaft, a bracket carried by said fixed shaft, a stud arranged in said bracket and 15 alined, and adapted to coact, with one of said rotary shafts to support a bobbin, an upright

carried by said fixed shaft, a rod arranged in said upright, another bracket carried by said rod, another stud arranged in said last-named bracket and alined, and adapted to coact, 20 with the other rotary shaft to support another bobbin, means for rotating said rotary shafts, and means for effecting the traverse of said traverse-rail, substantially as described.

In testimony that I claim the foregoing I 25 have hereunto set my hand this 28th day of March, 1905.

GEORGE WASHINGTON BROMLEY.
